UNITED STATES PATENT OFFICE.

SAMUEL H. BRUNDIGE, OF HEALDSBURG, CALIFORNIA, ASSIGNOR OF ONE-THIRD TO JOHN C. BUTTERMORE AND ONE-THIRD TO ARTHUR L. BRUNDIGE, OF HEALDSBURG, CALIFORNIA.

ENGINE.

No. 896,514.

Specification of Letters Patent.

Patented Aug. 18, 1908.

Application filed March 30, 1908. Serial No. 424,124.

To all whom it may concern:

Be it known that I, SAMUEL H. BRUNDIGE, citizen of the United States, residing at Healdsburg, in the county of Sonoma and State of California, have invented new and useful Improvements in Engines, of which the following is a specification.

My invention relates to improvements in engines or motors in which a pair of pistons is adapted to reciprocate to and from each other in cylinders lying parallel with each other.

My invention consists in the novel connections of the pistons of each of a pair of cylinders so that they operate in unison, and the power developed in each cylinder is transmitted to each of a pair of cranks upon the common crank shaft.

It also consists in valve mechanism whereby the impelling fluid is admitted to and exhausted from the cylinders; and in details of construction which will be more fully explained by reference to the accompanying drawings, in which—

25 Figure 1 is a horizontal section of my invention as applied to double-acting engines. Fig. 2 is an end view of the valve. Fig. 3 is a side view of the valve.

The cylinders A and B are mounted upon any suitable supporting frame. I have here shown such a frame at C. Within each cylinder are pistons 2 and 3. The pistons 2 have piston rods 4 extending through the rear ends of their cylinders, with suitable stuffing-boxes 5 where the engines are to be double-acting, as when steam or similar impelling fluid under constant pressure is employed. The pistons 3 have piston rods 6 extending through similar stuffing-boxes 7 at the front end of the cylinders, and these piston rods are connected with cross-heads 8 slideable upon guides 9. From the cross-heads, connecting rods 10 extend to the cranks 11 upon the crank shaft 12, which has suitable journal boxes as at 13.

45 The piston rods 4 have right-angled extensions 4^a exterior to the rear cylinder heads, and these rods are again bent as shown at 4^b, so that this second bend brings the rods into position parallel with the piston rods 4 themselves; and these parallel extensions 4^b pass between the cylinders A and B, and connect respectively with the cross-heads 8 of the opposing cylinders; that is to say, the piston rod 4 of

the cylinder A, extending out through the rear of the cylinder is bent at right angles as 55 at 4^a, then again bent to form the extension 4^b, and this is connected with the cross-head 8 of the cylinder B. In like manner the piston rod of the cylinder B forms two bends passing between the cylinders, and connects 60 with the cross-head 8 of the cylinder. Thus each of the rear pistons 2 is directly connected with the cross-head of the other cylinder, and as the cranks 11 are at 180 degrees of each other, it will be seen that one piston 2 will be 65 approaching the center of the cylinder, while the other is receding therefrom. At the same time, the piston 3 of the first cylinder will be approaching the piston 2 in the same cylinder, while the piston 3 of the other 70 cylinder will recede from the center in unison with the movement of the piston 2 in the same cylinder; this action being insured by the connection of the rear pistons to each cylinder with the cross-head and crank of the opposite cylinder. The cross-heads and guides of these cylinders are set at such a point as to 75 divide the power applied to them through the piston rods 6 and the extension rods 4^b, and for this purpose I have found that the guides 80 and cross-heads may be approximately midway between the line of travel of the forward piston rods, and the rods 4^b which connect with the same cross-heads.

When the impelling fluid is under constant 85 pressure as steam or compressed air, it may be admitted and exhausted to and from the spaces between the pistons 2 and 3, and when the pistons have thus been forced to the outer ends of their respective strokes, the 90 impelling fluid may be admitted at the outer ends of the cylinders to force them back again; thus making each pair of pistons double-acting in its own cylinder.

Various valve mechanisms may be employed for this purpose. In the present case I have shown hollow rotary valves 15—15^a the latter being located near the ends of the cylinders and the former being located near the intermediate part of the cylinders, said 100 valves being turnable in valve chambers 16 which are located between the cylinders, and out of the line of movement of the rods 4^b. These valves are actuated by a rod or shaft 17 having upon the end contiguous to the 105 shaft a bevel-gear 18 which meshes with a

similar gear 19, mounted upon the crank shaft, the proportions being such that the valves make a complete revolution for each revolution of the main shaft.

5 The ports are so disposed that when the valves are in proper position to admit the impelling medium between the pistons 2 and 3 of the cylinder A, the ports from the ends of the said cylinder will communicate with the 10 exhaust passages 20; at the same time the ports at the ends of the cylinder B will be opened, and the pistons of that cylinder being at opposite ends will be impelled toward the center. The exhaust port from the center 15 of this cylinder will then be open to the exhaust passage 20, and the flow of the impelling medium will be such that power is applied alternately from the center and ends of each cylinder, so that one pair of pistons is 20 being impelled outwardly, while the other pair is being impelled toward each other, and by reason of the connection of each of the pistons 2 of the respective pistons with the cross-heads of the opposite cylinders, the 25 power applied to the front pistons in each cylinder will be transmitted directly to the crank shaft through the cross-heads and connecting rods, while the power from the rear pistons will be transmitted through the supplemental connecting rods to act in unison 30 upon the cross-heads, connecting rods and cranks of the opposing cylinders.

It will be manifest that the same construction may be applied to internal combustion engines of either two or four cycle type; the same connections being made between the pistons of the cylinders and the cranks of the opposing cylinders.

Having thus described my invention, what 40 I claim and desire to secure by Letters Patent is—

1. The combination in an engine of a shaft having opposed cranks, a pair of cylinders, two pistons movable in each of the cylinders, 45 cross-heads for said pistons, means by which one of the pistons of a cylinder is connected directly with its own cross-head, and the other piston is connected indirectly with the cross-head of the other cylinder, means for

admitting an impelling medium between the 50 pistons, and means connecting each of the cross-heads with one of the cranks.

2. In an engine, a shaft having opposed cranks, guides with cross-heads slideable in line with the cranks, rods connecting the 55 cross-heads with the cranks, cylinders each having two pistons, one of which is connected directly with its own cross-head and crank, and the other is connected indirectly with the cross-head and crank of the opposite cylinder, valves by which the impelling medium is admitted to impel the pistons of the two 60 cylinders in opposite directions in unison.

3. In an engine of the character described, a shaft having opposed cranks, cylinders arranged side by side, connecting rods from the 65 cranks, cross-heads to which they are united, and guides upon which the cross-heads slide in line with the cranks, two pistons movable in each cylinder, the front pistons having offset connections with the cross-heads, and the rear pistons having offset connections with the cross-heads of the opposite cylinders, with offsets substantially equal to and balancing those of the forward pistons. 70

4. In an apparatus of the character described, a pair of cylinders each having two pistons, a shaft having opposed cranks, a cross-head for each piston and guides for the cross-heads, one of said pistons being connected directly with its own cross-head and crank and the other piston being connected indirectly with the cross-head and crank of the opposite cylinder, valves located between the cylinders having ports through 85 which the impelling medium is alternately admitted between the pistons and exterior thereto, and so timed that the pistons of one cylinder are moving outwardly, while those of the other cylinder are moving inwardly. 90

In testimony whereof I have hereunto set my hand in presence of two subscribing witnesses.

SAMUEL H. BRUNDIGE.
